MAGAZINE CATCH AND RELEASE.

1,307,492.

Specification of Letters Patent. Patented June 24, 1919.

Application filed December 1, 1917. Serial No. 204,924.

To all whom it may concern:

Be it known that I, GRANT HAMMOND, a citizen of the United States, residing at New Haven, in the county of New Haven and 5 State of Connecticut, have invented a new and Improved Magazine Catch and Release, of which the following is a specification.

My invention relates to the class of devices employed to receive ammunition and to be placed in a firearm for the use of the ammunition therein, and an object of my invention, among others, is to provide simple and effective means for holding such a device in place and for automatically effecting its discharge when it is empty.

One form of device embodying my invention and in the construction and use of which the objects herein set out, as well as others, may be attained, is illustrated in the accompanying drawings, in which—

Figure 1 is a view in lengthwise section through a magazine embodying my invention, a breech-bolt being shown in dotted lines.

Fig. 2 is an edge view of the same with parts broken away to show construction, the line of view being substantially at right angles to the axis of the magazine and the catch being shown in its releasing position.

Fig. 3 is a view similar to Fig. 2, but with cartridges in the magazine, and further illustrating that portion of the handle with which the catch engages and the relative location of the breech-bolt with respect to the magazine when it is in place, the magazine catch being shown in position to hold the magazine in the handle.

Fig. 4 is a detail side view of the lower part of the handle of a firearm embodying my invention.

In the accompanying drawings the numeral 5 indicates a portion of the frame or handle of my improved firearm, 6 a portion of a grip piece, and 7 the breech-bolt, all of which parts may be of any suitable form and material.

My improved magazine 8 may be of any suitable form to fit within the handle of the firearm in a manner common to devices of 50 this class, said magazine containing a follower spring 9 pressing upwardly against a follower 10 upon which cartridges 23 rest in a way that will be readily understood.

The bottom 11 of the magazine may be secured in place in any efficient manner and 55 a locking bolt recess 12 therein receives a locking bolt 13 and that is seated against a locking bolt spring 14 in the bottom of the recess. The end of the bolt is arranged to engage a keeper socket in the frame or handle and a bolt actuating lever 15 is pivotally mounted on the bottom with one end operatively engaged with the locking bolt, the other end being connected as by a chain or other extensible flexible connection 16 with 60 the follower 10. In the special form of construction herein shown the lever 15 is a bell-crank lever, one end being engaged in a notch 17 in the locking bolt. In one form of bolt contemplated by me the end of the 65 bolt is forked providing two prongs, one of which 18 constitutes a locking prong that enters a keeper socket 19 in the frame, and the other prong 20 of which constitutes a thumb piece projecting outwardly into a recess 21 in the outer surface of the handle and by means of which the bolt may be manually actuated to release the magazine.

From the above description, taken in connection with the accompanying drawings, it 70 will be understood that when the magazine is fully loaded the follower 10 will occupy its lowermost position, and as the cartridges are successively moved into the barrel by the operation of the breech-bolt 7 the follower 75 will gradually rise. The chain or connection 16 is of such length that it will be drawn taut preferably by further movement of the follower after the last cartridge in the magazine has been forced into the barrel and 80 after the follower has been brought to rest against the under side of the breech-bolt as shown in Fig. 1 of the drawings, the chain being of such length that at this time no 85 force is exerted to disengage the locking bolt 13 from its keeper. It will now be understood that when the firearm is operated to fire the last cartridge which has been thus placed in the barrel, the breech-bolt will be forced backwardly and will be retained in 90 this position in a manner common to automatically acting firearms, in connection with which my improved magazine is designed to be employed. When the breech-bolt has 95 passed backwardly in this firing operation 100 the latter will spring 105 beyond the follower 10.

- upwardly and consequently the connection 16 will be drawn taut and the lever 15 will be actuated to withdraw the locking bolt 18 from its keeper and the magazine will fall 5 by gravity or otherwise from its chamber 24 in the handle, the thumb piece 20 in this operation passing out through a slot 22 in the bottom portion of the handle. The end of the locking prong 18 is curved or beveled 10 so that when the magazine is inserted in the opening in the magazine chamber in the handle the engagement of this cam shaped end with the bottom edge of the handle or slot therein will force the locking bolt back- 15 wardly, in which position the wall of said chamber will retain it until the prong reaches a position opposite the keeper socket 19 when the bolt will be snapped by the spring 14 into its socket.
- 20 It will be noted that as the follower 10 gradually, in its feeding movement, approaches the open end of the magazine the distance between the lever 15 and said follower gradually increases, that is, the fol- 25 lower is separated from the lever and the flexible connection 10 is extensible in that it permits separation of said lever and follower without operating the lever until said connection has been extended to its 30 full length. It will therefore be seen that other forms of extensible connections may be employed to accomplish this same purpose and without departing from the spirit and intent of the invention.
- 35 In accordance with the provisions of the patent statutes, I have described the principles of operation of my invention, together with the device which I now consider to represent the best embodiment 40 thereof; but I desire to have it understood that the device shown is only illustrative and that the invention may be carried out by other means.
- I claim—
- 45 1. A magazine for a firearm, said magazine including a follower, a catch to retain the magazine in place in the firearm, and an extensible connection between the follower and magazine catch for operation of the latter.
- 50 2. A magazine for a firearm, said magazine including a follower, a catch to retain the magazine in place in the firearm, and an extensible connection secured to the fol- 55 lower and to the catch and of a length to be drawn taut to operate the catch when the follower reaches its limit of movement in the magazine.
- 60 3. A magazine for a firearm, said magazine including a follower, a catch located at the lower end of the magazine to engage the handle of the firearm to retain the magazine in place, and an extensible connection between said follower and catch of a length 65 to be drawn taut when the follower reaches

substantially the limit of upward movement in the magazine.

4. A magazine for a firearm, said magazine including a locking bolt having a locking prong and a prong serving as a thumb 70 piece by means of which the bolt may be manually operated, and means for automatically operating said bolt.

5. A magazine for a firearm, said magazine having a locking bolt the end of which 75 is forked with branches of different lengths, the shorter branch serving as a locking bolt and the longer branch as a thumb piece by means of which the bolt may be disengaged from a keeper.

6. A magazine for a firearm, said magazine including a follower, a bolt catch, a bolt actuating lever operatively engaging the catch, and a flexible extensible connection between said lever and follower.

7. A magazine for a firearm, said magazine including a follower, a bolt catch located in the lower end of the magazine and adapted to engage a keeper, a lever pivotally mounted in the lower end of the magazine and operatively engaged with said catch, and a flexible extensible connection between said follower and the lever and of a length to be drawn taut at substantially the time the follower reaches the limit of its 95 upward movement.

8. A firearm including a handle having a magazine chamber therein, a keeper recess in the lower end of the handle, a magazine to fit said chamber and having a bolt catch to engage said keeper in the handle, a follower within the magazine, and a flexible extensible connection between the bolt catch and follower and of a length to be drawn taut at substantially the time the follower reaches the upper limit of its movement.

9. A firearm including a handle having a magazine chamber with a keeper socket in the wall of said chamber, and a slot opening into a recess in the outer surface of the handle, a magazine fitting said chamber, and a bolt located in the magazine and having a prong to engage said keeper and another prong located in said slot and recess 110 to serve as a thumb piece whereby the bolt may be manually operated.

10. A firearm including a handle having a magazine chamber therein with a keeper socket in the wall of said chamber and a 115 slot opening into a recess in the outer surface of the handle, a magazine to be located in said chamber, a lever pivotally mounted in the magazine, a follower movably mounted in the magazine, and a flexible extensible 120 connection between said follower and lever to actuate the latter.

11. A firearm having a magazine chamber therein, a magazine having a follower, a catch to retain the magazine in place in 130

said chamber, and an extensible connection actuated by the follower to operate the catch to release the magazine.

12. A firearm having a magazine chamber 5 therein, a catch to retain the magazine in said chamber, a magazine containing a follower having cartridge feed movement therein away from said catch, and a connection actuated by the follower to operate 10 the catch to release the magazine.

13. A firearm having a magazine chamber therein, a catch to retain the magazine in said chamber, a magazine containing a fol-

lower having cartridge feed movement 15 therein away from said catch, and a connection attached to said follower and catch and arranged to permit movement of the follower without operation of the catch until the follower has reached a predetermined position.

14. A magazine for a firearm, said magazine including a follower, a bolt catch, a bolt actuating lever operatively engaging the catch, and means carried by the follower to operate the lever to release the magazine. 20 25

GRANT HAMMOND.
